UNITED STATES PATENT OFFICE.

REESE R. JONES AND THOMAS W. JONES, OF ST. LOUIS, MISSOURI.

MEANS FOR GREASING THE NECKS OR JOURNALS OF ROLLING-MILL ROLLS.

SPECIFICATION forming part of Letters Patent No. 718,471, dated January 13, 1903.

Application filed August 5, 1902. Serial No. 118,496. (No model.)

To all whom it may concern:

Be it known that we, REESE R. JONES and THOMAS W. JONES, of the city of St. Louis, State of Missouri, have invented certain new and useful Improvements in Means for Greasing the Necks or Journals of Rolling-Mill Rolls, of which the following is a full, clear, and exact description, reference being had to the accompanying drawings, forming a part hereof.

Our invention relates to means for greasing the necks or journals of rolling-mill rolls; and it consists of the novel construction, combination, and arrangement of parts herein-after shown, described, and claimed.

The object of our invention is to provide improved means for automatically greasing the necks or journals of black plate and other sheet-plate, hot or cold rolls. Heretofore the greasing of such necks or journals has usually been accomplished by the handwork of men and boys at considerable expense and often with unsatisfactory and variable results.

In the drawings, Figure 1 is a plan view of a set of common rolls for sheet metal having our invention applied thereto. Fig. 2 is a side elevation of same with parts broken away. Fig. 3 is a detail sectional side elevation of the rolls, showing the application of the grease-carrying swabs to the necks of the rolls. It shows the construction from a point of view opposite that of Fig. 2. Fig. 4 is a detail sectional view of the grease-pot and the swab-chain connections thereto. Fig. 5 is a detail sectional elevation of a portion of the swab-chain.

1 indicates a common set of rolls having the usual necks or journals 2, mounted in the ordinary frame 3. Mounted in the space between the necks of the upper and lower rolls 1 is a frame 4, having a plurality of plugs or pins 5 fixed thereto, and mounted upon said pins are a series of small sprocket-wheels 6 and also a flanged roller 7. The two upper sprocket-wheels 6 are mounted in horizontal alinement, so that the swab-carrying chain 8 may run over the same and be drawn for a short distance parallel to the neck 2, and after passing over the said alined sprocket-wheels said chain 8 passes downwardly and beneath another sprocket-wheel, which is located closely adjacent the neck of the lower

roll, and then said chain passes upwardly and over the flanged roller 7 and thence passes downwardly into the grease-pot 9, 55 which is preferably located at a point beneath the floor and supported by means of nails or bolts, such as 10, which connect the same to the base or foundation. Mounted upon an arm 11 at a point near the bottom of said 60 grease-pot is a flanged roller 12, around which said chain travels, and the function of which is to cause the said chain to travel near to the bottom of said pot. The arm 11 forms a part of the extra frame 4 and is connected to 65 the upright bar 13 by means of suitable bolts or rivets 14, and said upright bar is secured to the base by means of suitable bolts or other fastenings. Carried by said chain 8 are series of swabs 15, which are preferably made 70 of some absorptive material, such as a body of flannel or felt, although they may be of any other suitable material, and they are secured to the links of the chain 8 by means of metallic loops 16, which project from the outer 75 face of said chain-links at suitable distances apart. (See Fig. 5.)

A suitable shield or wiper 17 is secured to the arm 11 immediately above the grease-pot and is curved downwardly at its upper end, 80 so as to be contacted by the swabs 15 as they emerge from the grease-pot, and thereby be relieved from any excess of grease. This wiper may be adjustably secured in position by means of a suitable bolt or other fastening 18 and is preferably made of sheet metal. The excess thus removed from the swabs will of course gravitate into the grease-pot beneath.

We have thus far described our invention 90 as applied only to the necks and one end of the rolls 1; but it is obvious that the same may be duplicated and applied to the opposite end of said rolls or to any number of rolls or sets of rolls.

In some cases we prefer to provide an additional vertical chain 19 and a horizontal endless chain 20, by means of which power may be communicated to the adjacent swab carrying chains of the additional sets of rolls. 100

21 and 22 indicate the shafts carrying the sprocket-wheels for the said additional chains.

Power is applied to the rolls in the usual manner through the shaft 23, which may be

provided with a belt or pulley 24 or any other suitable power-transmitting device.

Power to drive our improved neck-greas-
ing machine is preferably taken from the shaft
5 23 by means of a suitable chain 25 and is
transmitted thereby to the sprocket-wheel
having an integral clutch member 26, which
parts are mounted to slide loosely upon a coun-
ter-shaft 27, which carries the fixed member
10 28 of said clutch. A suitable hand-lever 29
is pivoted at 30 and engages the loose mem-
ber 26 of the said clutch, so as to slide the
same, together with its integral sprocket-
wheel, on the said counter-shaft 27 when it is
15 desired to start or stop the greasing-machine.
31 indicates the bearings for the said coun-
ter-shaft. Mounted upon the inner end of
the said counter-shaft is a bevel gear-wheel
32, which transmits motion to another bevel
20 gear-wheel 33, which is mounted upon a short
shaft 34, extending at right angles to the said
counter-shaft and mounted in suitable bear-
ings 35 and which carries sprocket-wheels
which impart motion to the swab-chain 8 and
25 the additional chain 19.

The operation is as follows: The rolls 1 be-
ing set in motion by means of power trans-
mitted through the shaft 23, the chain 25 will
30 then cause the counter-shaft 27 to be revolved,
and motion will be communicated from the
latter through the bevel-wheels 32 to the short
shaft 34, and this will cause the swab-chain
8 to travel over its supporting-wheels, and the
35 swabs 15 will be immersed in the grease con-
tained in the grease-pot 9 and will absorb a
quantity of said grease and carry the same
upwardly past the wiper 17, and thence over
the alined sprocket-wheels beneath the upper
40 roll-neck 2, and thence downwardly and
under the sprocket-wheel just above the neck
of the lower roll, and thence over the flanged
roller 7, and thence downwardly to the grease-
pot. The swabs 15 in passing the said roll-
45 necks will automatically supply an ample
amount of grease to them.

We do not limit ourselves to the exact con-
struction herein shown and described, as it is
obvious that the same may be varied within
the skill of a mechanic without departing from
50 the scope of our invention.

What we claim is—

1. An automatic device constructed with
an endless traveling chain carrying absorbent
swabs, to take grease from a distant pot and
55 apply the same to the necks or journals of
rolling-mill rolls, substantially as specified.

2. The combination with rolling-mill rolls
having the usual necks or journals, of a se-
ries of chain - supporting rollers arranged
closely adjacent said rolls, a chain adapted
60 to travel over said rollers, a grease-pot lo-
cated at a distance from the said necks, means
for causing the said chain to run into the
said pot, absorbent swabs carried by said
chain and arranged to be brought into con-
65 tact with the said necks, and means for im-
parting motion to the said chain, substantially
as specified.

3. The combination with rolling-mill rolls
having the usual necks or journals, of a chain
70 arranged to travel in a line parallel with the
axis of the said necks, suitable rollers and
wheels for supporting said chain in close prox-
imity to said necks, absorbent swabs carried
75 by said chain, a source of grease to which said
chain extends, and means for imparting motion
to the said chain, substantially as speci-
fied.

4. The combination with rolling-mill rolls
having the usual necks or journals, of a chain
80 arranged to travel in a line parallel with the
axis of the said necks, suitable rollers and
wheels for supporting said chain in close prox-
imity to said necks, absorbent swabs carried
85 by said chain, a source of grease to which said
chain extends, means for imparting motion
to the said chain, and a wiper for removing
excess of grease from said swabs after they
90 leave said source of grease, substantially as
specified.

5. The combination with rolling-mill rolls
having the usual necks or journals, of a chain
95 arranged to travel in a line parallel with the
axis of the said necks, suitable rollers and
wheels for supporting said chain in close prox-
imity to said necks, absorbent swabs carried
by said chain, a source of grease to which said
chain extends, means for imparting motion
100 to the said chain, a wiper for removing ex-
cess of grease from said swabs after they leave
said source of grease, and means for starting
and stopping said chain while the movement
of said rolls continues, substantially as speci-
fied.

In testimony whereof we affix our signa-
tures in presence of two witnesses.

REESE R. JONES.
THOMAS W. JONES.
